(57) **CLAIM**

The ornamental design for a base for seating unit, as shown and described.

DESCRIPTION

FIG. 1 is a top, front, right perspective view of a base for seating unit embodying our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken line representations in the figures show unclaimed environment, and thus form no part of the claimed design.

The nature of this product is a base for a seat for supporting a human in a seated position.
